(57) **CLAIM**

The ornamental design for a video case for mobile phone, as shown and described.

DESCRIPTION

FIG. 1 is a front perspective view of a first component of a video case for mobile phone according to a first embodiment showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear perspective view of a second component of the video case for mobile phone according to the first embodiment;

FIG. 9 is a front elevational view of FIG. 8;

FIG. 10 is a rear elevational view of FIG. 8;

FIG. 11 is a left side elevational view of FIG. 8;

FIG. 12 is a right side elevational view of FIG. 8;

FIG. 13 is a top plan view of FIG. 8;

FIG. 14 is a bottom plan view of FIG. 8;

FIG. 15 is a front perspective view of the video case for mobile phone according to the first embodiment;

FIG. 16 is a front elevational view of FIG. 15;

FIG. 17 is a cross-sectional view of FIG. 16, taken along lines 17-17 of FIG. 16;

FIG. 18 is an enlarged detail view of the encircled region of FIG. 1;

FIG. 19 is an enlarged detail view of the encircled region of FIG. 2;

FIG. 20 is an enlarged detail view of the encircled region of FIG. 4;

FIG. 21 is an enlarged detail view of the encircled region of FIG. 8;

FIG. 22 is an enlarged detail view of the encircled region of FIG. 10;

FIG. 23 is an enlarged detail view of the encircled region of FIG. 17;

FIG. 24 is a front perspective view of a first component of a video case for mobile phone according to a second embodiment;
 FIG. 25 is a front elevational view of FIG. 24;
 FIG. 26 is a rear elevational view of FIG. 24;
 FIG. 27 is a left side elevational view of FIG. 24;
 FIG. 28 is a right side elevational view of FIG. 24;
 FIG. 29 is a top plan view of FIG. 24;
 FIG. 30 is a bottom plan view of FIG. 24;
 FIG. 31 is a rear perspective view of a second component of the video case for mobile phone according to the second embodiment;
 FIG. 32 is a front elevational view of FIG. 31;
 FIG. 33 is a rear elevational view of FIG. 31;
 FIG. 34 is a left side elevational view of FIG. 31;
 FIG. 35 is a right side elevational view of FIG. 31;
 FIG. 36 is a top plan view of FIG. 31;
 FIG. 37 is a bottom plan view of FIG. 31;
 FIG. 38 is a front perspective view of the video case for mobile phone according to the second embodiment;
 FIG. 39 is a front elevational view of FIG. 38;
 FIG. 40 is a cross-sectional view of FIG. 39, taken along lines 40-40 of FIG. 39;
 FIG. 41 is an enlarged detail view of the encircled region of FIG. 24;
 FIG. 42 is an enlarged detail view of the encircled region of FIG. 25;
 FIG. 43 is an enlarged detail view of the encircled region of FIG. 31;
 FIG. 44 is an enlarged detail view of the encircled region of FIG. 33;
 FIG. 45 is an enlarged detail view of the encircled region of FIG. 34; and,
 FIG. 46 is an enlarged detail view of the encircled region of FIG. 40.

Although the claimed subject matter of the video case for mobile phone, in which the claimed design is embodied, consists two components, the claim is directed to the ornamental appearance of the claimed subject matter of the video case for mobile phone as an entirety, and does not extend to the ornamental appearance of each of the individual components.

The dash-dash broken lines in the drawings depict the portions of the video case for mobile phone that form no part of the claimed design.

The dot-dash broken lines in FIGS. 1-2, 4, 8, 10, 17-25, 31, 33-34, and 40-46 form no part of the claimed design; they

delineate portions of the video case for mobile phone, including claimed subject matter, that are shown on an enlarged scale in FIGS. 18-23 and 41-46. The dashed broken lines throughout the drawing figures form no part of the claimed design; they depict portions of the video case for mobile phone that form no part of the claimed design.
